UNITED STATES PATENT OFFICE

HARRISON J. L. FRANK, OF HIGHLAND PARK, MICHIGAN, ASSIGNOR TO BULL DOG ELECTRIC PRODUCTS COMPANY, OF HAMTRAMCK, MICHIGAN, A CORPORATION OF WEST VIRGINIA

SELECTIVE FUSE PLUG SHELL

Application filed February 14, 1930. Serial No. 428,231.

This invention relates to current take off devices, such as fussed plugs.

The devices of the invention are particularly designed for use with the electrical distribution system shown in my prior applications, Ser. No. 424,428, filed Jan. 29, 1930; and Ser. No. 434,102, filed May 20, 1930.

Fused plugs are not broadly new, being shown in the patent to Kollath 1,743,821, Jan. 14, 1930, among others, but the fuse plug of this application contains novel details which form the principal objects of the invention.

One of the objects is a plug which may be varied in length to accommodate cartridge fuses of various lengths and capacities.

Another object is a plug having a fuse concealing shell which may be moved to expose one and only one, of the fuses, at any one time, whereby the exposed fuse may be removed and replaced without disassembling the device, even in part.

A further object is a plug of the type described in the foregoing paragraph, wherein the shell is so interlocked with the receptacle with which it cooperates that movement of the shell for fuse exposure, is not possible unless and until the plug has been withdrawn from the live receptacle, this feature preventing fuse manipulation while the fuse is alive.

A further object is a plug having grounding means which effectively grounds the plug to the distribution conduit, before the plug can be plugged into the receptacle, until after the plug is withdrawn from the receptacle, and all the while the plug is plugged in the receptacle.

A further object is a plug which has projecting contacts, readily convertible from the knife blade or male type, to the parallel leaf or female type.

A further object is a plug made of a number of stock parts, assembled as desired, to create plugs of different capacities.

A further object is a plug having parts designed to afford maximum electrical insulation consistent with compactness.

Still further objects will readily occur to those skilled in the art upon reference to the following description and the accompanying drawings in which

Fig. 1 shows a fused plug of the invention, in use.

Fig. 2 is a top plan view of one form of plug.

Fig. 3 is a section on line 3—3 of Fig. 6. 55

Fig. 4 is a section on line 4—4 of Fig. 6.

Fig. 5 shows the plug mounting and holding means.

Fig. 6 is a section on line 6—6 of Fig. 4.

Fig. 7 is a section on line 7—7 of Fig. 4. 60

The plug

Referring to the drawings, and first of all to Figs. 4 and 6, it will be seen that the plug includes two complementary insulating portions 10 and 11, between which the fuses are disposed and from one of which project the plug contacts, and to the other of which the current conductors are connected. 65

The portion 10 is made of molded insulation, such as a phenolic condensation product, and is molded around the contacts 12. Projecting down from its lower face, Figs. 4 and 6, is a central section 13 of T contour, and from each outer point of the T, barriers 14 75 project radially to define peripherally spaced recesses 15, these containing ends of the contacts 12.

Each of the ends is provided with a threaded hole 16 into which may be threaded a screw 80 17 for securing a cartridge fuse clip 18 to the contact, the construction affording removability to the fuse clips.

The portion 11, complementary to the portion 10, is also made of molded insulation and is molded around the connecting lugs 21, these having binding posts 22 to which may be connected ends of conductor 23, leading to a machine or other current consuming device. Projecting upwardly from the upper face of 85 the portion 11 is a central T shaped section 24, from whose outer points radially project barriers 25, defining peripherally spaced recesses 26, these containing the ends of the connector lugs 21. These ends are provided 90 with vertically aligned threaded holes 27 into desired ones of which may be threaded screws 28 for securing cartridge fuse clips 29 to the lugs.

Fuses 30 may be snapped into the clips 18 100

and 29, thru the mouths of the recesses, and will serve to close electrical lines from contacts 12 to lugs 21 and conductors 23, and it will be seen that the electrical lines are relatively insulated by the complementary barriers 14 and 25.

The plug enclosure and details

The portions 10 and 11, together with their fuses, clips etc. are enclosed in a hollow cylindrical shell 32 of insulation, the same being capped at the plug contact end by a ring shaped annularly grooved casting 33 and at the cable end by a plate casting 34 thru which the conductors 23 pass. The shell 32 is rotatable between the castings and around the portions 10 and 11 and is provided with an opening 35 (Fig. 6) adapted to be registered with a selected one of the recesses, as desired, or with none of them, as desired. The casting 33 is provided with a friction leaf spring 36 (Fig. 4) to engage the shell, thereby restraining its rotation, although not absolutely preventing rotation.

If desired, a knob 37 on the leaf may be provided to engage in a depression in the shell, the engagement alining the shell with the casting, so that the shell opening is normally in registry with one of the barriers 14-25.

Although the fuses 30 tend to hold portions 10 and 11 to each other, in the shell, other and more reliable means may be provided, if desired, to attain this result, and such means are shown best in Fig. 3. The means includes long bolts 38 passed thru the portions and threaded at one end, into lugs 39 on the casting 33, and at the other end, provided with nuts, one of which 40 holds the portions 10 and 11 together, and the other of which 41 holds the casting 34 in place. The bolts pass thru the barriers 14-25 on the portions 10 and 11, and are surrounded by insulating tubes 42, which not only insulate the bolts from the spaces between the portions, but also serve to space the portions 10 and 11 at desired distances.

It will be observed that the length of the vertical space between the portions, and consequently the length of the shell 32, the bolts 38, and the tubes 42, depends upon the length of the fuses 30. Accordingly, when the plug is to accommodate low voltage or short fuses, short ones of the parts above mentioned will be chosen, but when the plug is to be used for high voltage or with long fuses, long ones of the parts will be selected. It will further be seen that to change a plug from one length to another, is a very simple matter, only certain, inexpensive, parts being substituted.

It will also be observed that plugs of large current carrying capacity will be provided with large fuse clips easily mounted in the tapered recesses 15-26, whereas lower amperage plugs will contain smaller fuse clips.

Accordingly, the creation and reconstruction of plugs, for various electrical demands, is a simple and inexpensive matter.

In order to isolate respective contacts 12 and respective binding posts 22, and to reduce creepage, etc., barriers 45 are formed on the top surface of the portion 10 (Fig. 2) and barriers 46 are formed on the bottom surface of the portion 11 (Fig. 7). Contacts 12 are further isolated from each other, when live, by the walls 47 between the various outlet holes 48 on the outlet block 49 (Fig. 4) of the duct.

Further, while contacts 12 are shown as being of the blade or make type, to cooperate with leaf or female contacts 50 in the outlet block 49, they might well be of the leaf or female type, to cooperate with bare bus bars or with blade or male contacts, accessible thru or in the block.

It will be observed that one set of the barriers, 14-25 namely the one forming the legs of the T (Fig. 6) is extended peripherally so as to be of greater arcuate length than the opening 35 in the shell. Further, this barrier is provided with recesses 56 in which are seated nuts 57 thru which pass screws 58 for holding an arcuate insulating plate 59 against the barriers. The plate 59 bridges the space between the barriers 14 and 25 and prevents access to the inside of the plug, even when the shell opening 35 is in registry with that set of barriers. Accordingly, in normal use, the shell is so positioned by means of spring leaf 36 and knob 37, that its opening 35 registers with the plate 59. The latter may be made of a different color than the portions 10 and 11 so as to indicate its location by color contrast, and is made of the same color as the shell so as to make the plug in normal use, more attractive than would otherwise be the case.

The mounting, polarizing, interlocking and grounding details

In prior art plug devices, the friction and spring pressure between the plug and receptacle contacts is relied upon to maintain the plug and receptacle in conjunction. This practice is perhaps satisfactory, in some cases, but is not as reliable as might be desired. Accordingly, plug mounting means, which may be dispensed with, if desired, have been disclosed and the same will now be described, in connection with parts provided on the duct.

The duct 60 is provided on its lower surface with an opening around which is mounted a centrally apertured outlet plate 61, the latter having headed pins 62 passing upwardly thru slots 63 in parallel locking plates 64, there being coiled springs 65 for pressing the locking plates against the plate 61. The outlet plate, further has holes 66 in registry with locking plate keyhole slots 67, these

holes and slots receiving the headed pins 68 on the plug ring casting 33. When the plug is plugged into the receptacle 49, the plug pins 68 pass thru the holes 66 and the large parts of the keyhole slots 67, after which the locking plates are shifted to cause the small parts of the keyhole slots 67 to line up with the holes 66, thus locking the plug to the outlet plate.

10 The outlet plate and receptacle as a unit, is so mounted on the duct as to be polarized with respect to the bus bars therein, and since the plug can be inserted in the receptacle in only one position, it will be seen that the plug is automatically polarized with respect to the bus bars. Accordingly, once a motor is equipped with a properly wired plug, insertion of the latter in a manner which will cause rotation of the motor in a proper direction, is automatically and perpetually insured.

It may be desired to prevent access to the interior of the plug, for fuse renewal or for any other reason, except when the plug is not "live" and accordingly interlock means, shown best in Fig. 3, are provided, such means including a slideable spring pressed plunger 70 mounted in the ring casting 33 and having a pin 71 adapted to ride in a slot 72 of the casting 33 and a slot 73 of the shell 32. When the plug is not plugged in, that is to say, when it is not "live" the plunger is advanced and the pin 71 is out of the shell slot 73, the shell thus being free to be rotated to expose the fuses. When the plug is plugged into the duct outlet, however, and is "live", the plunger is retracted and the pin 71 is disposed in the slot 73, preventing the shell from being rotated. Further, the slot 73, shell opening 35 and plunger 70 are so located with respect to each other, that the slot 73 must be in line with plunger pin 71, and opening 35 must be in registry with insulating plate 59, before the plunger can be retracted to permit plugging-in of the plug. Accordingly, it is impossible to plug-in while any fuse or line in the plug is exposed.

Further, the plunger 70 projects beyond the contacts 12, and must therefore be retracted by its engagement with the duct before the contacts 12 can make with the outlet contacts 50. Accordingly, the plug enclosure is grounded to the grounded duct before the plug is made live. As a corollary, the plug enclosure is grounded to the duct all the while the plug is live, and even shortly after the plug is pulled out of the receptacle.

It will further be noted that upper casting 33 completely closes the receptacle opening when the plug is in circuit, thus sealing the live parts of the plug in the plug shell and the duct.

Now having described the invention and

the preferred embodiment thereof, it is to be understood that the said invention is to be limited, not to the specific details herein set forth but only by the scope of the claims which follow.

What I claim is:

1. In a fused plug adapted for operative connection with a bus bar structure a central space-enclosing cap provided with means for detachably engaging the bus bar structure, thereby to hold the plug in place, a peripherally recessed, intermediate section of insulating material, pairs of relatively spaced contact members in the recesses of said intermediate section, each being provided with a fuse clip, one of each pair of said contact members terminating in a binding post located at one end of said intermediate section, the other one of each pair of said contact members being terminally formed as a plug contact which projects into and is surrounded and protected by the central space enclosed by said cap, a second cap positioned on the opposite end of said intermediate section from that engaged by the first mentioned cap, longitudinally extending rods for holding the parts in assembled relation, and a rotatably mounted shell of insulating material surrounding said intermediate section and having an aperture adapted to be registered with a selected one of the recesses of said intermediate section to afford access thereto for inspection or replacement of a fuse therein positioned.

2. In a fused plug, a pair of terminal caps, one of which is provided with a peripheral flange defining a central protective recess and with peripherally disposed means for detachably engaging parts of a bus bar structure, means for detachably holding said caps in desired spaced relation, an intermediate member of insulating material having a plurality of peripherally spaced and peripherally accessible recesses wherein fuses may be positioned in isolation from one another, a pair of spaced fuse clips positioned in each of said recesses, one of said clips being provided with a binding post positioned at one end of said intermediate member, the other of said clips being provided with a plug contact which projects into and is surrounded by the peripheral flange of the adjacent one of said caps, and a rotatably mounted insulating shell surrounding said intermediate member and adapted to protect said fuse-housing recesses from external access, said shell having an aperture adapted to be moved into registry with selected ones of said recesses as the shell is rotated.

3. In a fused plug, a peripheral body of insulating material having peripheral recesses, each containing a fuse, the walls between the recesses isolating the fuses, a pair of terminal members spacedly supported within each of said recesses, each being pro-

vided with a fuse clip, one of each pair of terminal members having its end contoured to binding post form, the end of its companion member projecting from the opposite end of said insulating body and formed as a plug 5 contact, terminal plates positioned at the ends of and secured to said body of insulating material, that one of said plates adjacent said projecting plug contacts having a peripheral skirting which forms a protective recess into 10 which said plug contacts project, means appurtenant said last mentioned terminal plate for detachably connecting it and accordingly, the body to a bus bar structure and thereby effecting an electrical contact between said 15 projecting plug contacts and the bus bar structure, and a rotatably mounted insulating shell surrounding said peripherally recessed body and adapted to protect the fuses positioned in the several recesses against external access, said shell having an aperture 20 adapted to be moved into registry with selected ones of said recesses as the shell is rotated.

4. In a fused plug adapted for operative connection with a bus bar structure, a plate 25 provided with means for detachably engaging the bus bar structure, means for preventing the complete connection of said plug and bus bar structure until a ground connection 30 therebetween has first been made, said plate also having a centrally located recessed portion, a peripherally recessed body of insulating material having one end engaging said 35 plate, a pair of circuit terminals spacedly disposed in each of the recesses of said insulating body, one of each pair of said terminals having end portions in the form of plug contacts which project into the central 40 recess of said plate, the other of the terminals in each recess projecting beyond the opposite end of said insulating body to provide a conductor binding portion, a second plate forming a cap over the last mentioned end of the 45 insulating body, a fuse clip carried by each of said terminals in said recesses, and a rotatably mounted, insulating shell surrounding said recessed insulating body and having an aperture adapted to afford access to selected 50 ones of said recesses and to the fuse positioned therein only when the shell is rotated to such position that its aperture registers with the recess.

5. A fused plug comprising an intermediate insulating block provided with a plurality of peripherally accessible recesses, a pair of relatively spaced fuse clips positioned in each of said recesses, each pair being adapted to be connected by and detachably support a fuse positioned in said recess, a protective frame for said block comprising end plates and connecting rods, one of said plates being formed for detachable connection with a bus bar structure when properly positioned thereon, and a protective insulating shell rotat-

ably positioned about said insulating block and provided with an access aperture whereby access to any of said recesses is permitted only when the aperture is registered therewith, and plug terminals projecting from one 70 of each pair of fuse clips.

6. Means for detachably and accessibly supporting a plurality of fuses in insulated and normally protected position, comprising a cylindrical block of insulation having 75 spaced peripherally accessible recesses, a rotatably mounted protective shell surrounding the block and having an aperture thru which access to selected ones of said recesses is permitted when the aperture is in registry therewith, a pair of spaced fuse clips positioned in each of said recesses, a plug contact extending from one of each pair of clips beyond the end of said block, and structurally connected protective plates positioned at the ends of said block, one of said plates having a skirt adapted to protect said plug contacts, said plate being also formed for temporary interlocking engagement with a bus bar structure when 80 properly positioned on the latter.

7. In a fused plug, a body of insulating material provided with spaced, laterally opening recesses, means in each of said recesses for detachably supporting a fuse, a plug contact connected to each fuse and extending through one end of said body, a frame for said body and its supported elements and for protecting said plug contacts, means on said frame for detachably securing said plug in operative relation to current-carrying elements, and a shell rotatably supported by said frame to conceal said recesses, said shell having an aperture thru which may be had access to selected ones of said recesses, when the aperture is in registry with any one thereof.

8. In a fused plug, a frame provided with means for permitting the detachable operative installation of the plug on a distribution system, an insulating body within said frame and provided with peripherally opening recesses, fuses in said recesses, a shell rotatably supported by said frame and surrounding said body, said shell having an aperture adapted to be registered with selected ones of said recesses and means for preventing rotative movement of said shell when the plug is connected to said distribution system.

9. In a fused plug, a pair of spaced end sections, each containing a fuse clip, a fuse connecting and supported in said clips, cable connection means on one of said sections and plug contacts on the other, and means comprising elongated rods removably positioned in the sections and connecting them for maintaining them in assembly, the rods being insulated from the space between the sections.

10. In a fused plug having an end section provided with plug contacts and an apertured, rotatable, fuse-concealing shell, means

- on the end section for preventing rotation of the shell when the plug contacts are in engagement with cooperating contacts, the means also preventing the plug contacts from being engaged with cooperating contacts while the shell is not in fuse concealing position. 5
11. In a fused plug, spaced end sections of insulation having peripherally accessible fuse containing recesses separated by radially extending barrier walls of insulation, a rotatable insulating shell surrounding said end sections and having an aperture adapted to be registered with selected ones of the recesses 10 and barriers, and an insulating plate connecting the adjacent radially projecting ends of one pair of barriers to conceal the space between that pair of barriers and thereby 15 between the sections at that barrier. 20
12. In a fused plug, a pair of spaced end sections, each containing a fuse clip, a fuse connecting and supported in said clips, cable connections means on one of said sections and plug contacts on the other, and means comprising elongated rods removably positioned in the sections and connecting them for maintaining them in assembly, the rods being insulated from the space between the sections by tubes of rigid, form-sustaining insulation 25 whose ends engage the sections to separate them. 30
13. In a fused plug having an end section, plug contacts, and an apertured, rotatable, fuse-concealing shell, means on the end section for preventing rotation of the shell when the plug contacts are in engagement with cooperating contacts, the means also preventing the plug contacts from being engaged with cooperating contacts while the shell is not in 35 fuse concealing position, the means also serving to ground the plug. 40
14. In a fused plug having an end section provided with plug contacts and an apertured, rotatable, fuse-concealing shell, means 45 on the end section for preventing rotation of the shell when the plug contacts are in engagement with cooperating contacts the means also preventing the plug contacts from being engaged with cooperating contacts 50 while the shell is not in fuse concealing position, the means also serving to ground the plug automatically, before, during the time that and shortly after, the plug contacts are engaged with their cooperating contacts. 55
15. In a fused plug, spaced end sections of insulation having peripherally accessible fuse containing recesses separated by radially extending barrier walls of insulation, a rotatable insulating shell surrounding said end 60 sections and having an aperture adapted to be registered with selected ones of the recesses and barriers, and an insulating plate connecting the adjacent radially projecting ends of one pair of barriers to conceal the space 65 between that pair of barriers, and thereby be- 70
- tween the sections at that barrier, the plate and the barrier ends when combined, being of a greater arcuate length than that of the shell apertures. 75
16. In a fused plug, spaced end sections of insulation having peripherally accessible fuse containing recesses separated by radially extending barrier walls of insulation, a rotatable insulating shell surrounding said end sections and having an aperture adapted to be registered with selected ones of the recesses and barriers, and an insulating plate connecting the adjacent radially projecting ends of one pair of barriers to conceal the space between that pair of barriers and thereby 80 between the sections at that barrier, and means on the plug for normally insuring the registry of the shell aperture with the plate. 85
17. In a fused plug, spaced end sections of insulation having peripherally accessible fuse containing recesses separated by radially extending barrier walls of insulation, a rotatable insulating shell surrounding said end sections and having an aperture adapted to be registered with selected ones of the recesses and barriers, and an insulating plate connecting the adjacent radially projecting ends of one pair of barriers to conceal the space between that pair of barriers and thereby 90 between the sections at that barrier, and means on the plug for normally insuring the registry of the shell aperture with the plate and for preventing movement of the shell from such registered position, when the plug is "live". 95
18. In a fused plug having a shell and fuses therewithin, means for mounting the plug on and connecting it to a current distribution system, said shell being mounted so as not to be movable to fuse exposing position when the plug is in connection with said system, 100 said shell, when in fuse exposing position, further preventing mounting said plug on and connecting it to said shell. 105
- In testimony whereof I sign this specification. 110
